(57) **CLAIM**

The ornamental design for a spade shaped carabiner, as shown and described.

DESCRIPTION

FIG. 1 is a top or bottom plan view, which are mirror images, of my new design for a spade shaped carabiner.

FIG. 2 is a right elevation view of the carabiner shown in FIG. 1.

FIG. 3 is a left side elevation view of the carabiner shown in FIG. 1.

FIG. 4 is a front side elevation view of the carabiner shown in FIG. 1.

FIG. 5 is a rear side elevation view of the carabiner shown in FIG. 1.

FIG. 6 is a top perspective view of the carabiner shown in FIG. 1.

FIG. 7 is a top or bottom plan view, which are mirror images, of an alternate embodiment of my new design for a spade shaped carabiner.

FIG. 8 is a right elevation view of the carabiner shown in FIG. 7.

FIG. 9 is a left elevation view of the carabiner shown in FIG. 7.

FIG. 10 is a front elevation view of the carabiner shown in FIG. 7.

FIG. 11 is a rear elevation view of the carabiner shown in FIG. 7; and,

FIG. 12 is a top perspective view of the carabiner shown in FIG. 7.
